UNITED STATES PATENT OFFICE

2,480,739

ROTARY DISK TYPE SCRAPING BRUSH
HEAD WITH REMOVABLE RADIAL
BLADES

Franklin D. Johnson, Battle Creek, Mich.

Application April 29, 1947, Serial No. 744,719

1 Claim. (Cl. 15—93)

1

This invention relates to new and useful improvements and structural refinements in meat block brushes, more specifically, in a meat block brush constituting the subject matter of U. S. Patent No. 2,101,394, which was granted to me on December 7, 1937.

While experimenting with a brush constructed in accordance with the teachings of the aforesaid patent, it has been found that the same lends itself to certain structural and operational improvements, whereby the construction thereof may not only be considerably simplified, but its functional utility may also be considerably enhanced.

It is, therefore, a primary object of the instant invention to provide a device which embodies such improvements in its construction and which, like the original invention, consists of a rotary brush assembly, such as may be guided by hand across the surface of the meat block, so as to clean and scrape the wood for the purpose of removing foreign matter therefrom.

A further object of the invention is to provide a brush which may be directly attached to and driven by a conventional electric hand drill with the chuck thereof removed, or alternatively, which may be remotely actuated through the medium of a flexible drive cable.

Another object of the invention is to provide a meat block brush which is simple in construction, which will not easily become damaged, and in which the brush members, when worn, may be easily and conveniently replaced.

An additional object of the invention is to provide a meat block brush which will readily lend itself to economical manufacture and which is otherwise adapted for the purpose for which it is intended.

With the above more important objects in view, and such other objects as may become apparent as this specification proceeds, the invention consists essentially of the arrangement and construction of parts as illustrated in the accompanying drawings, in which:

Figure 1 is a perspective view of the invention, showing the same in association with an electric hand drill, the chuck of the latter being removed.

Figure 2 is an underside plan view of the brush head per se.

Figure 3 is a cross sectional view, taken substantially on the plane of the line 3—3 in Figure 2.

Figure 4 is a cross-sectional view, taken substantially in the plane of the line 4—4 in Figure 3.

Figure 5 is a cross-sectional view, taken substantially in the plane of the line 5—5 in Figure 3.

2

Figure 6 is an exploded perspective view of a shell and cover used in the invention.

Figure 7 is a perspective view of one of the spacer blocks.

Figure 8 is a perspective view of another of the spacer blocks.

Figure 9 is a perspective view of one of the wedges used in association with the block shown in Figure 7.

Figure 10 is a perspective view of one of the brush members used in the invention, and

Figure 11 is a side elevational view of a protector hood, such as may be conveniently employed with the invention.

Like characters of reference are used to designate like parts in the specification and throughout the several views.

Referring now to the accompanying drawings in detail, the invention consists of a meat block brush designated generally by the reference character 15, the same embodying in its construction a circular disc 16 provided with a marginal flange 17 and forming a casing 18.

A hub member 19 is secured concentrically to the disc 16 by means of suitable screws 20, the member 19 being provided with a tubular shaft extension 21 which projects through a suitable opening formed in the disc 16 and constitutes a shaft, as it were, for the brush assembly as a whole. It will be noted that the attachment of the hub member 19 to the disc 16 is reinforced by an annular plate or washer 22, which is also held in position by the aforementioned bolts or screws 20.

A plurality of brush members 23 are radially disposed in the casing 18, each of these brush members consisting of an elongated plate provided in one longitudinal edge thereof with a series of notches defining a row of substantially rectangular fingers 24, as is best shown in Figure 10.

A circular cover 25 is receivable in the casing 18, the configuration of the cover being best shown in Figure 6, wherein it will be noted that

the cover consists of a central hub portion 26, a plurality of radially extending spokes or arms 27, and a marginal rim 28.

A plurality of tapered spacing blocks 29, preferably formed from hard rubber or the like, and best shown in Figure 8, are interposed between the plates forming the brush members 23. It will be noted that these spacing blocks as well as the brush members, are arranged in such manner that the fingers 24 of the brush members may project outwardly through the openings 30 formed between the cover spokes 27.

Further spacing blocks 31, having a tapered configuration, are positioned immediately over the spokes 27, and it should be understood that

while the aforementioned blocks 29 are tapered

longitudinally so as to facilitate the assembly of the brush members 23 in the radial formation, the blocks 31 are tapered longitudinally as well as in the "thickness" thereof, so that a pair of complementarily tapered wedges 32 may be positioned immediately adjacent the blocks 31, as is best shown in Figure 5.

The brush members 23, the blocks 29 and 31, as well as the wedges 32 are provided at the inner and outer ends thereof with suitable notches or recesses forming inner and outer sets of keeper seats 33, 34 respectively. These seats are so arranged that when the cover 25 is applied to the casing 18 and an annular keeper ring 35 is positioned adjacent the inner surface of the cover, the keeper ring will be received in the outer set of seats 34 and will thereby assist in retaining the components 23, 29, 31 and 32 in position.

It should be understood that the cover 25 is removably retained in position by means of a plurality of bolts or screws 36 which extend through suitable apertures formed in the spokes 27 and in the blocks 31, and pass through further apertures provided in the disc 16.

A further keeper ring 37, equipped with an annular, projecting shoulder 38, is interposed between the aforementioned hub member 19 and the hub portion 27 of the cover 25, the shoulder 38 of the ring 37 being receivable in the inner set of keeper seats 33, as is best shown in Figure 3. Needless to say, the ring 37 is retained in position by the aforementioned bolts or screws 20, as will be clearly apparent.

It will be found that when the brush is assembled, the clamping of the cover 25 upon the blocks and wedges 29, 31 and 32 will assure that the brush members 23 are rigidly retained in position, primarily by virtue of the resiliency of the blocks 29. Thereupon, the drive shaft 21 of the brush may be secured in any suitable manner to a convenient source of power, as exemplified in Figure 1 by an electric hand drill 39, from which the conventional chuck assembly has been removed.

The entire device may then be applied to the meat block (not shown) by holding the handles 40, 41 of the electric drill assembly, and engaging the fingers 24 with the surface of the block. The blocks 29, interposed between the members 23, will function as shock absorbers or cushions, thereby allowing the brush to work smoothly on uneven surfaces and increasing the life span of the brush members 23.

After the fingers 24 have become worn, the brush members 23 may be quickly and easily replaced by simply separating the cover 25 from the casing 18, whereby immediate access to the components 23, 29, 31 and 32 may be had.

If desired, the operator may protect himself against flying particles of foreign matter by installing a protector hood 50 over the brush assembly 15.

This hood is shown in the accompanying Figure 11, and consists of a suitable casing 51 which is adapted to receive the brush assembly 15 therein. The casing 51 is provided with a suitable extension 52 whereby it may be mounted on the head portion 53 of the drill 39, the extension 52 being, in turn, with a suitable extension 54 through which the handle 40 may project.

The lower edge portion of the casing 51 is equipped with an annular band 55 formed from flexible material such as leather or the like, the

band 55 being attached to the casing 51 by a plurality of rivets, or the like, 56. The band 55 will, of course, permit the brush fingers 24 to be brought into contact with the meat block surface, while at the same time, particles of foreign matter will be prevented from flying in the direction of the operator.

It should be noted that by virtue of the flexible band 55, the entire brush assembly may be manipulated on uneven surfaces, such as are usually found on meat blocks.

Finally, it may be added that while the accompanying drawings illustrate the invention as being directly attached to the hand drill 39, the drive shaft 21 of the brush assembly may be operatively connected by means of a length of flexible cable to any suitable source of motive power, whereby the brush assembly will assume a portable character, in which form it may be conveniently manipulated by hand, without carrying the drill motor assembly 39 as a component part thereof.

It is believed that the advantages and use of the invention will be clearly apparent from the foregoing disclosure and accordingly, further description at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

A meat block brush comprising in combination, a circular disc provided with a marginal flange and forming a casing, a drive shaft secured to said disc, a plurality of radially disposed brush members positioned in said casing, each of said members comprising an elongated plate formed in one longitudinal edge thereof with a series of notches defining a row of substantially rectangular fingers, a plurality of tapered spacing blocks interposed between said plates, said plates and said blocks being notched at the ends thereof to form inner and outer sets of keeper seats, a circular cover receivable in and removably secured to said casing, said cover being formed with openings, said fingers projecting outwardly through said openings, and a pair of keeper rings each engaging one set of said seats, said rings being removably retained in position by said cover.

FRANKLIN D. JOHNSON.
